Filed Oct. 24, 1965, Ser. No. 87,896

Term of patent 14 years

(Cl. D29—1)

Fig. 1

FIGURE 1 is an elevational view of a Christmas tree ornament showing my new design, the opposite side being the same;

The stippled area indicates an enclosed foam ball.

I claim:

The ornamental design for a Christmas tree ornament, as shown and described.
